MEANS FOR WINDING THREAD OR THE
LIKE

Tom Grogan, Cleveland, Ohio, assignor to Industrial Rayon Corporation, Cleveland, Ohio, a corporation of Delaware

Application March 11, 1938, Serial No. 195,350

1 Claim. (Cl. 242—53)

This invention relates to apparatus for the manufacture of thread or the like characterized by a large number of filaments.

In the processing on thread-advancing thread store devices of thread or the like made up of a large number of filaments, difficulties are encountered due to the fact that the thread or the like tends to spread out in the form of a flat, ribbon-like mass. This tendency, unless restricted, results in overriding of the filaments of adjacent turns, causing breakage, snarling, etc., of the individual filaments. Such knots, snarls and broken filaments pile up on the guide means provided to direct the thread or the like to the next device, thereby impeding normal thread travel and, if not removed, subjecting the thread or the like to so high a tension as to cause it to break.

The present invention contemplates the introduction of suitable means for preventing the thread or the like from spreading to such an extent as to give rise to the aforementioned difficulties. The interposition of such means in conjunction with an appropriate form of thread-advancing thread store device, preferably at a point between the thread-receiving and the thread-discharge ends thereof, accomplishes a two-fold purpose; namely, preventing undue spreading of the thread or the like and tending to wrap within the thread or the like the weakened and/or broken filaments which frequently occur in the production of thread or the like. The latter feature not only preserves the strength of the individual filaments, but prevents their catching on guides employed to direct the thread or the like to the succeeding thread-advancing thread store device.

The invention finds application in the handling of any thread or the like made up of a large number of filaments, but for present purposes has been illustrated and will be hereinafter described as applied to the processing of viscose filament bundles intended to be cut into fibers of staple length.

In the accompanying drawing, which represents but one of a variety of possible embodiments of the invention, Figure 1 represents a front elevation of a portion of a machine embodying a series of thread-advancing thread store devices, together with associated distributors, guides and troughs; Figure 2 is an enlarged end elevation of a single thread-advancing thread store device; Figure 3 is a plan of the apparatus of Figure 2; Figure 4 is a side elevation of the same thread-advancing thread store device, together with its

associated apparatus; and Figure 5 is a section with parts in elevation along line 5—5 of Figure 2. In the drawing, like reference characters refer to like parts throughout.

The thread-advancing thread store devices of the present invention preferably take the form of and will hereinafter be referred to as reels, although in lieu thereof any other desired type of thread-advancing thread store device may be employed.

In Figure 1 of the accompanying drawing, reels 1, 8, 9 and 10 are illustrated more or less diagrammatically as of cantilever form; i. e., supported and driven from the thread-receiving end thereof and having the thread-discharge end thereof unobstructed by anything impeding continuous discharge of the filament bundle. Thus the discharge ends of all reels are presented to the operator for inspection, manipulation, maintenance, etc. Although the reels may be disposed in any of several equally suitable arrangements serving to facilitate progression of the filament bundle from one reel to the next, reels 1, 8, 9 and 10 are arranged obliquely with their respective axes parallel to each other and with the thread-discharge end of each reel in apposition to the thread-receiving end of the next succeeding reel.

The filament bundle 6 is supplied to reel 1 from any desired source of supply such as suitable thread-forming means or from one or more previous reels. It advances along reel 1 in a series of closely spaced, generally helical turns until it reaches the discharge end of the reel, from which it is directed by guide 11 to reel 8. Upon the periphery of the latter it is further advanced toward the discharge end, from which point it is directed by a similar guide 11 to reel 9, and so on. The series of reels may be made up of any appropriate number of reels sufficient to perform the desired processing treatments.

Processing treatment may be accomplished on the reels by the application to the filament bundle of one or more processing reagents. Such reagents may be supplied from any suitable source such as a distributor 12 which may be connected with a supply conduit (not shown). The reagent showered upon the reel is caught in trough 13 connected by the drain pipe 14 either to the sewer for the removal as waste or to a make-up reservoir for recirculation if the reagent is of such a nature that it may advantageously be reused. The troughs, distributors and associated apparatus may be supported upon any suitable framework.

As has been previously mentioned, any form of thread-advancing thread store device may be used in connection with the apparatus of the present invention. A typical reel capable of being employed for the purpose is shown in detail in Figure 5 of the accompanying drawing and will be explained briefly herein. A more detailed description may be obtained by referring to prior application Serial No. 652,089 for "Winding reel" filed by Walter F. Knebusch on January 16, 1933 (Patent 2,210,914). The reel shown in Figure 5 of the accompanying drawing differs from the reel therein disclosed principally in that it is of cantilever form.

The reel comprises two rigid cage members 17 and 18 made up of a plurality of longitudinally extending bar members 19 and 20 alternately disposed with respect to each other. Reel member 17, referred to as the concentric member, consists of a supporting structure comprising disc 21 secured to a drive shaft 22 by the set screw 23, said disc 21 supporting bars 19. The second reel member 18, referred to as the eccentric member, is provided with a supporting disc 25 mounted so as to rotate freely upon the frame member 26 in which is journaled shaft 22. The bearings therefor are so arranged that the axes of the cage members 17 and 18 are in offset and inclined relation with respect to each other.

By reason of the above-described arrangement, when the drive shaft 22 is rotated the cage member 17 mounted concentrically upon and fixed thereto likewise rotates and, because of the interdigitating relation of bars 19 and 20, drives member 18 by bar-to-bar contact. In addition, the relative radial displacement of the bars causes the filament bundle to be supported first by one set of bars and then by the other, while the inclined relation causes it to advance longitudinally of the reel. Together, both actions result in progressing the filament bundle from one end of the reel to the other substantially in the form of a helix composed of a series of closely spaced turns.

Referring again to Figure 1, filament bundle 6 is advanced along each of the reels 7, 8, 9 and 10 in the series from the thread-receiving to the thread-discharge end thereof, being meanwhile subjected to processing treatment as above explained.

In the processing of filament bundles on such reels, especially where such processing is accomplished by the introduction of a liquid reagent, the filament bundle tends to assume a flat ribbon-like form while being advanced upon the surface of the reel. This tendency to assume a flat ribbon-like form is sometimes detrimental in that the application of the reagent causes the filaments at the outer edges of one turn to wash together with filaments at the outer edges of adjacent turns, causing said filaments to override and become entangled. This action gives rise to slubs taking the form of knots, snarls, or bunches which adhere to the thread as it is advanced, either being torn loose, thereby fouling other turns of thread, or being carried along and deposited upon the guides.

Pursuant to the invention, gathering means for condensing the filament bundles into more compact form are disposed at any suitable point between the thread-receiving and thread-discharge ends of the reels. Such gathering means may take any suitable form. In the embodiment of the invention herein illustrated said gathering means are shown in their simplest form;

i. e., that of an auxiliary guide 27. As shown, said auxiliary guide 27 is similar in shape to guides 11, but mounted some distance in from the point of discharge of the filament bundle.

In the threading-up operation, as filament bundle 6 reaches a point near the discharge end of the first reel 7, the end of said filament bundle 6 is threaded over auxiliary guide 27 adjustably mounted upon an arm 28 secured to the trough 13 which surrounds each reel, passed around the end of the reel 7 for one or more additional turns, then led to the guide 11 adjustably fastened to the trough 13. From guide 11 it passes to the thread-receiving end of the next reel 8 and so on throughout the entire series of reels. In some instances it may be found satisfactory to cause filament bundle 6 to make only a single additional turn about the end of reel 7 after leaving auxiliary guide 27 before threading it through guide 11; in others, to cause it to make several turns on the reel between guides 27 and 11.

In order to insure flexibility of operation, auxiliary guide 27 may be mounted in a block 29 which is secured to the arm 28 by a wing nut 30 in the slot 31 (Figure 3). This arrangement permits not only changing the position of auxiliary guide 27 if it is desired to increase the number of turns on any of the reels between said guide and the discharge end of said reel but also adjusting the location of the guide for helices of different pitch. It is obvious that various other arrangements of the auxiliary thread guide 27 and other elements of the apparatus described may be employed to accomplish the same general purpose.

The use of some sort of auxiliary guide interposed between the thread-receiving and thread-discharge end of each reel prevents the aforementioned flattening action of the filament bundle from continuing to the point where overriding, snarling and tangling of filaments results. The guide serves, among other things, to condense the filaments into a generally round bundle. The latter action on the part of the guide folds in any broken or weakened filaments, which further tends to strengthen the filament bundle as a whole and prevent the formation of slubs.

As hereinabove stated, although the illustrated embodiment of the invention is primarily directed to the application of the invention to the processing of viscose filament bundles adapted to be cut into fibers of staple length, the invention should be understood as equally adaptable to any known method of processing of any thread or thread-like articles. Other forms of apparatus may be employed without departing from the spirit of the invention. It is intended that the patent shall cover, by suitable expression in the appended claim, whatever features of patentable novelty reside in the invention.

What is claimed is:

Apparatus for handling a thread bundle consisting of a large number of individual filaments which, by reason of the manner of its handling, assumes a flat, substantially ribbon-like form comprising, in combination, a thread-advancing thread store device serving to advance the thread bundle in a helix of closely spaced turns each of which, due to flattening of the thread bundle, tends to spread into contiguity with the others as the thread bundle nears the zone in which it is to be discharged from said thread store device; a housing surrounding said thread store

2,251,212

device, said housing consisting of back, bottom and two side walls; and, mounted on one of the walls making up said housing, means supported in spaced relation to the periphery of said thread store device at a point adjacent the zone of discharge of the thread bundle for dis-

engaging the penultimate turn of the helix from the periphery of said thread store device and condensing the filaments thereof into a compact, generally round rope-like bundle.

TOM GROGAN.
